DISPENSING DEVICE

Filed Dec. 31, 1923

FIG. 1.

FIG. 2.

Inventor:

HARRY S. LEVINTHAL

By *Stone & Bain Mfg. Co.* *Attest.*

Patented Nov. 11, 1924.

1,515,127

UNITED STATES PATENT OFFICE.

HARRY S. LEVINTHAL, OF MELROSE PARK, ILLINOIS.

DISPENSING DEVICE.

Application filed December 31, 1923. Serial No. 683,627.

To all whom it may concern:

Be it known that I, HARRY S. LEVINTHAL, a citizen of the United States, residing at Melrose Park, in the county of Cook and

5 State of Illinois, have invented certain new and useful Improvements in Dispensing Devices, of which the following is a specification.

The invention relates to devices for accurately dispensing small quantities of liquids.

One of the objects of the invention is to provide an easily controlled device for dispensing small admeasured quantities of liquid from a bottle and which may be used 15 without moving the bottle.

A further object is to provide an attachment to a bottle, or other similar container, for use by druggists in preparing prescriptions and by other dispensers of liquids.

20 A further object is to provide a device whereby a very large portion of the liquid content may be removed therefrom without moving the bottle from its upright position.

A further object is to provide a reminder 25 that the supply of liquid is about exhausted before the available supply is entirely gone.

Another object is to provide a device for a receptacle that is self closing when not in use, making it sanitary and substantially air 30 tight.

Other objects and advantages of the invention will hereinafter appear from a consideration of the following description, when taken in conjunction with the drawings, wherein:

Fig. 1 is a vertical central section thru a bottle and the dispenser showing a reciprocatable plunger to compress air in the bottle.

40 Fig. 2 is a modification showing a flexible globe as a means for compressing air.

In both views the same reference characters are employed to indicate similar parts.

The dispensing device consists of a stopper 45 5 which may be of glass or other suitable material. In Fig. 1 the stopper is preferably of glass, having a bore 6 communicating with the interior of a bottle 7, at 8. A plunger 9 loosely fits the bore so that it may

50 be reciprocated and normally closes a port 10 in a metal cap 11. A spring 12 normally holds the plunger elevated. A stem 13 is secured in the plunger and carries a thumb piece 14 on its upper end.

55 A pipe 15 passes thru the stopper to a point 16 near the bottom of the bottle. The

pipe 15 is bent at substantial right angles at 17. Its end terminal is oblique at 18. A closure 19 overlies the opening 18 to normally close the pipe.

60 A pair of uprising arms 20 from the cap 11 afford pivotal support for a lever 21 which carries the closure 19 and which is pivoted at 22 between the arms 20. The free end 23 of the lever 21 is slotted and extends about the stem 13 under the thumb piece 14. A pin 24 under the end 23 lifts the lever to operate the closure when the spring 12 lifts the plunger 9 and stem 13.

65 The operation of the device will be clearly 70 understood.

Pressure on the thumb piece depresses the plunger against the stress of the spring and drives air in the bore 6 into the bottle at the same time the end 23 of lever 21 is depressed and the outer end of the pipe 15 is simultaneously opened by removal of the closure 19. The introduction of air under pressure 75 causes displacement of liquid in the pipe 15 which will flow out of the end 18 in a small stream or in drops depending upon the speed and extent of movement with which the plunger is moved.

80 When the plunger is moved downwardly it opens vent 10 in cap 11 and prevents tendency to formation of a vacuum above the plunger. When the plunger is returned by the spring it closes the vent and at the same time the closure 19 closes the end 18 of the pipe 15.

85 When liquid level in the bottle descends to the end 16 of the pipe 15 it is noticed to the dispenser that an order for replenishment should be entered. After this condition has developed an additional quantity of 90 the liquid may be extracted by tilting the bottle, so that the side near the end 16 is lower than the opposite side.

95 When the device is not in use the bottle is sealed.

In Fig. 2 the means to compress air is the elastic, compressible globe 9' and the lever 21 has a spoon shape end 23' which overlies the globe and which is depressed by pressure of the operator's thumb thereon.

100 The cap 11 may be held on the stopper 5 by a screw 25 passing thru ears 26, or otherwise.

105 The device is valuable because of the ease with which it is operated and the perfect control of the liquid dispensed. Furthermore, the device saves the dangerous neces-

sity of lifting and tilting the bottle, an act which causes a large per cent of breakage and expensive waste of the contents, as the device may be operated by one hand without lifting the bottle from the shelf.

Having described my invention what I claim as new and desire to secure by Letters Patent, is:—

A dispensing device comprising a container and a separable stopper device having two parallel axially extending bores; an air compressing means associated with one bore to force air into the container; a

pipe extending into the container and thru the other bore in the stopper and deflected laterally from the stopper; a band extending around the outer end of the stopper and clamped thereto providing means to pivotally support a lever and a lever pivoted to said support having one end overlying the outer end of the pipe to normally close the pipe and its other end extending to the air compressing means.

In testimony whereof I hereunto set my hand.

HARRY S. LEVINTHAL.
